COLLAPSIBLE DISPLAY AND LECTURE STAND

Jean De Jen, Fairfield, Conn.

Application December 26, 1947, Serial No. 793,959

3 Claims. (Cl. 248—197)

1

This invention relates to display and lecture stands particularly of the easel type and preferably having structural features which enable the easel legs to support the work backing frame or "board" of the stand at greater height above the floor than above a table.

In easel construction as heretofore proposed the easel legs themselves have commonly served as the sole means of backing flexible work sheets in upstanding position. When such work sheets are to be written on, as during a chalk talk or educational lecture, they require the additional use of a stiff flat "board" to provide all-over backing support for the full area of the sheet. When the easel is to be carted frequently to different places such backing boards must be carried about as a bulky article separate from the easel itself.

A purpose of the present improvements is to unify into a composite structure a stiff flat board of substantial broadside area for backing large work sheets, with legs adapted to support such board upright in easel fashion. Particularly the invention aims to provide legs which shall be attached permanently to the board and yet may be folded into a compass no larger than the area of the board and flat against the board in a manner to avoid objectionable increase of the thickness of the board when conditioned for storage or for being carried about.

Other purposes of the invention are to make the combined board and legs extremely light in weight as well as adapted to be instantly convertible from a condition for use to a condition for transportation or storage. Another aim is to attain increased sturdiness in the combined structure as compared with ordinary easels both when my improved easel board is standing on its legs and when collapsed into carrying condition.

Another object is to provide in my unified board and easel structure hinge joints for the legs so constructed and arranged that the legs are dependably rigid when extended to stand on the floor yet leave available for use when folded into collapsed condition an abbreviated sort of foot structure by means of which the board may be supported in easel fashion upon a table top with its bottom edge only slightly elevated thereabove.

Other objects of the improvements are to provide means which will act automatically and dependably to retain one or more of the legs releasably in fixed relation to the board in either their extended or folded conditions while making unnecessary any attention to separate fastening means. It is also desirable to provide optionally usable shelf rests at different height levels on the

2

front legs which members shall be individually collapsible into a non-projecting position when not in use.

An easel satisfying the above objectives will in effect serve the several purposes of a portable drawing board, a display stand for large placards, or a dark room projection screen. For the latter purpose, as well as for extreme lightness of weight, these improvements contemplate constructing the "board" member of flat thin metal such as sheet aluminum suitably surface finished to possess the desirable good light reflecting qualities of a projection screen.

These and other features of the improvements will appear in greater detail from the following description of a successful embodiment of the invention wherein reference is made to the accompanying drawings in which:

Fig. 1 is a perspective rear view of my improved easel board with legs extended and upstanding on a floor.

Fig. 2 is a front perspective view of the same easel board showing the use of collapsible shelf rests for supporting the lower edge of a large upstanding placard or display sheet.

Fig. 3 is a front perspective view of the easel board with two of its legs fully folded and its third leg section folded up but slanting outward from the board to afford bracing support upon a table.

Fig. 4 is a perspective view of the rear of the board with all of the legs folded flat thereagainst.

Fig. 5 is a perspective view on an enlarged scale showing one of the hinge joints partially cut away to expose more clearly the construction of its several parts.

Fig. 6 is a correspondingly enlarged perspective view of two of the shelf rests shown respectively in collapsed and extended positions.

Fig. 7 is a cross sectional view taken through the center of the pivot pin of a hinge joint looking lengthwise of the leg in the direction of arrow A in Fig. 5 when the leg is folded into its fully collapsed position shown in Fig. 4.

Fig. 8 is an enlarged view looking toward the end of a folded leg in the direction of arrow B in Fig. 4.

Fig. 9 is an enlarged view taken in section crosswise through the retaining clamp for the intermediate leg in Fig. 4.

Fig. 10 is an enlarged fragmentary perspective view of the top hinge joint which pivotally connects the intermediate leg to the easel board in Fig. 1.

Fig. 11 is an enlarged perspective view looking in the direction of arrow C in Fig. 1 showing the

elongated slots in the intermediate leg that accommodate sliding movement of the leg braces.

Fig. 12 is a fragmentary view looking in the direction of arrow D in Fig. 5 taken in section centrally through a yieldable detent that holds the legs in extended position.

In the embodiment of the invention illustrated in the drawings there is a frame structure permanently incorporating the flat rigid surface 10 sometimes herein called a "board" but which I prefer to make of smooth surfaced, truly flat, sheet aluminum. It need not be more than $\frac{1}{8}$ inch thick if adequately reinforced by cleats 12 as herein shown to maintain it stiff and flat. The front of this "board" has a planar face which may be conditioned to serve as a good reflector of light by any of well known treatments commonly employed in making metal projection screens for the showing of pictures projected in a dark room. While for convenience the flat rigid frame 10 has been referred to as a "board" it may equally well and for some of the purposes of this invention comprise a skeleton frame structure that is made up of several pieces attached rigidly together preferably in flush or coplanar relationship. Except for the need of backing support for thin sheets 60 while the latter are being marked upon, the flat sheet of aluminum herein proposed to serve as a board 10 may be perforate to any practicable degree for further reducing its weight.

Flat against the rear surface of board 10 may be secured thereto by rivets 18, or otherwise, the two hollow stiffening cleats 12 laterally spaced apart near respectively opposite edges of the board. To these may be added as many other cleats or stiffening means as may be needed to increase rigidity.

For light weight and convenience of manufacture I choose to make the hollow cleats 12 from a running length of light gage channel strip which may be bent into incomplete tubular form of rectangular profile and from sheet aluminum.

This improved display and lecture stand assumes certain characteristics of an easel through a novel arrangement of its folding legs. Its two side legs 13, herein termed a pair of main or floor legs, are laterally spaced and between them there is a sectional or articulated intermediate bracing leg composed of stiff end-to-end sections, the lower of which sections is herein referred to as the foot section 14 and the upper of which sections is referred to as the hip section 14'. The two side legs 13 are swingable on horizontally spaced hinge pins 18 which establish the pivotal axes of hinge structures or pivotal joints that are fixedly related by being mounted on the rear of board 10 near the bottom edge thereof. The bracing leg 14' swings in relation to the board 10 about a hinge pin 19 that forms a third pivotal joint or hinge structure fixedly related to pins 18 by being mounted on the rear of board 10 near the top edge thereof. Thus the hinge structures incorporating pins 18, 18 and 19 comprise pivotal joints spaced apart on board 10 in locations related like the corners of a plane triangle. This arrangement coupled with the fact that all of these hinge pins have parallel horizontally directed pivotal axes is a feature that is novel with these improvements and a feature that gives rise to important advantages hereinafter explained. The planar face of board 10 is forward of the plane of such triangle and thereby not interrupted by the pivotal joints above described.

Hinge pin 18 (Fig. 10) may comprise one or more headed-over coaxial loose rivets as shown

in Fig. 10, or there may be substituted a through bolt or other common expedient for pivotally coupling leg 14 to the angle brackets 20 that are fixed on board 10 by rivets 21.

Each of the hinge structures at 18 includes a hinge bracket 25 in the form of a channel member bent up from sheet metal to a U-shaped cross sectional profile and which flanks three sides of the hollow cleat 12 and is fixed thereto by rivets 26. Bracket 25 is enough wider than cleat 12 to leave a gap at each side of the latter, as best shown in Fig. 7, and the rivets 26 are either shouldered at or pass through a shoulder-forming round spacer collar 27 whose thickness spans this gap. Thus room is maintained dependably between each side of cleat 12 and bracket 25 to receive freely the projecting flanges 28 of a hinge saddle 29 which closely flanks both sides of the end of leg 13, and as shown in Figs. 5 and 7 is fixedly fastened to leg 13 by rivets 30 thereby serving as a rigid terminal extension of leg 13. The hinge pin 18 forms a pivotal connection between the flanges 28 of saddle 29 and the sides of hinge bracket 25 and may consist of a screw or bolt held in place by the retaining nut 31. Flanges 28 are cut out at 32 to avoid interference with the spacer collars 27 when leg 13 is swung to its fully folded position shown in Fig. 4.

The broken line position of leg 13 and its hinge saddle 29 in Fig. 5 indicates the position of a rounded, struck-out detent boss 37 which may be formed on each flange 28 as shown in Fig. 12 to come into yielding interlocking register with a detent hole 38 in each side of the hinge bracket 25 when leg 13 is swung into straightaway alignment with cleat 12 as shown in full lines in Figs. 1 and 5. The rounded head of a stud fixed in flange 28 may be substituted for boss 37. In this open position of the leg, the top edge of the cross wall of saddle 29 is firmly thrust against the bottom edge of the hinge bracket 25 and acts as a stop at the point E indicated in Fig. 5 thus positively limiting the swinging movement of the leg in opening direction. Also, or alternatively, in the position of parts shown in full lines in Fig. 5 the proximate end of leg 13 may firmly abut against the end of cleat 12 which thus acts as a positive stop in exact register therewith. Thus until the hinge joint is deliberately broken by forcibly swinging the leg 13 counterclockwise toward its broken line position in Fig. 5, detent 37, 38 insures that the leg in its extended position shall serve as a dependably stiff, straightaway elongation of the cleat 12. The cross wall of saddle 29 may be omitted in which case the flanges 28 will be riveted separately and fixedly to the side walls of leg 13.

A pivotal joint or hinge structure like that of Fig. 5 is also built into the intermediate sectional articulated leg preferably at a point about midway its length whereupon the foot section 14 of this leg below this joint performs at this joint with respect to hip section 14' of the leg above the joint as does the leg 13 with respect to cleat 12 in Fig. 5. The axis of hinge pin 18 of this additional pivotal joint in the intermediate leg extends parallelly with the other pivotal axes of hinge structures 18 of the side legs and is carried bodily with the hip section 14' so as to swing into and away from coaxial relationship to said other pivotal axes as shown in Fig. 4. This enables floor leg 14 to be folded into closely overlapping relationship to frame 10 in the same manner as closed against the back of the frame structure legs 13 are foldable. Hence when the jointed intermediate leg is not folded at its mid

joint it is stiff and unitary throughout its length from the floor on which it stands to its top hinge bracket 20. In order to limit the degree to which bracing leg 14' can be swung backward away from board 10, bracing links 39 are pivoted respectively to the side walls of hollow cleats 12 and have their opposite ends in both pivotal and sliding engagement with elongated slots 40 in the side walls of the upper section of leg 14. The combined sliding and pivotal connection is afforded by studs 41 which are pivotally and slidably retained in slots 40 by any suitable means such as the thrust washer shown at 42 in Fig. 11.

Each of legs 13 and 14 is equipped at its bottom end with an insert 43 of rubber, fiber or other non-scratching material to provide a friction grip upon the floor, and at least one free end of each hinge bracket 25 carries a rubber disc 47 whose periphery serves as a foot pad on which the structure may rest on a table top as indicated in Fig. 3.

The bracing leg 14' together with its floor leg section 14, when folded flat against board 10 as shown in Fig. 4, are retained by spring clamps 48 as shown in Fig. 9. Legs 13 may be retained in their collapsed position shown in Fig. 4 by swingable wire loops 44 which are pivotally hooked in the side walls of cleats 12 as shown in Fig. 8.

For supporting large placards 49 or flat display charts in a position to lean against the board 10, each of legs 13 is equipped with a series of collapsible shelf rests 50 having forked ends 51 pivotally connected to the side walls of the leg by loose rivets 52 and having spring ears 53 which wipe into frictional clinging engagement with the side walls of the leg to retain the rest flat against the leg. When the shelf rest 50 is swung downward into projecting position for use, its wall edge 54 abuts against the front surface of the leg as shown in Fig. 6 and thereby limits the downward swing of the bracket to the projecting position shown. It will be noticed that the spring ears 53 serve an additional purpose in guarding the placard 49 against accidentally slipping forward off from the free end of the rest.

Figs. 1, 2 and 3 further show small bolts 58 penetrating board 10 and receiving thumb nuts 59 at the rear face of the board as an expedient for holding sheets of paper such as 60 against the board to be marked on by a lecturer in connection with his talk.

In its condition shown in Fig. 4 the collapsed stand is adapted to be carried about as a unit and can be set up very quickly and conveniently into condition for use as shown in Fig. 2 or Fig. 3, and with equal facility restored to its condition for cartage or storage shown in Fig. 4.

For use as a projection screen while standing on the floor, the easel will be conditioned as shown in Fig. 1, and when standing on a table will be conditioned for use as shown in Fig. 3. For use as a stand for displaying large placards such as 49, shelf rests 53 will be brought into use at chosen heights as shown in Fig. 2. There might be substituted for placard 49 a reflective plate to serve as a reflective screen on which pictures larger than the board 10 might be thrown. Fig. 2 also shows a pad of drawing paper removably fastened to the board by bolts and thumb nuts 59 so that the top sheet can be torn off as from a calendar leaving a fresh blank sheet with adequate backing support to be

marked on. Such pad could likewise be carried by the table supported board of Fig. 3.

Within the underlying principles of construction to which the appended claims are directed wide departures may be made from the particular shapes and arrangements of parts herein chosen to illustrate the present improvements and therefore the claims will be understood as intended to cover all variations of examples given which fairly would be embraced by the most inclusive meaning of the claim language.

I claim:

1. A collapsible display stand comprising in combination, a rigid work board having a rear broadside surface by which to be supported and an opposite front broadside display face to be maintained fully bare and accessible in both collapsed and erected conditions of the stand, a hip leg rigid from end to end overlapping said rear surface of the board having one of its ends hinged to the latter and having its other end free for swinging movement toward and away from the board, three floor legs, three hinge structures each incorporating a single hinge pin, two of said pins respectively coupling two of said floor legs to said rigid board and the other of said pins coupling the other of said floor legs to said free end of the rigid hip leg, and each of said hinge pins confining the floor leg coupled thereby to swinging movement about a single pivotal axis displaced rearwardly from said front display face of the board, and three pairs of mutually abutting stops, one stop of each pair being fixed on one of said floor legs, the other stop of two of said pairs being fixed on said rigid board, and the other stop of the third of said pairs being fixed on said rigid hip leg, said stops in each of said pairs mutually engaging in a manner to permit and restrict swinging movement of all of said floor legs from overlapping relation to said rear surface of said board to positions extending away from said work board, at least one of said hinge structures including a rigid channel member stationed fixedly on said rear surface of said board and a cooperative rigid channel member stationed fixedly on one of said floor legs, said channel members having mutually overlapping side walls penetrated by said hinge pin, and said stops comprising mutually abutting edges of said channel members, whereby said legs are precluded from swinging into overlapping relation to said front face of the board.

2. A collapsible display stand as defined in claim 1, in which one of the said side walls of one of the said channel members carries a rounded detentive boss projecting toward an overlapping side wall of the other of said channel members, and said overlapping side wall contains a pocket positioned to register with and receive said boss with releasable cling when the said edges of said channel members mutually abut.

3. A collapsible display stand comprising in combination, a rigid work board having a rear broadside surface by which to be supported and an opposite front broadside display face to be maintained fully bare and accessible in both collapsed and erected conditions of the stand, a hip leg rigid from end to end overlapping said rear surface of the board having one of its ends hinged to the latter and having its other end free for swinging movement toward and away from the board, three floor legs, three hinge structures each incorporating a single hinge pin, two of said pins respectively coupling two of said floor legs to said rigid board and the other of

said pins coupling the other of said floor legs to said free end of the rigid hip leg, and each of said hinge pins confining the floor leg coupled thereby to swinging movement about a single pivotal axis displaced rearwardly from said front display face of the board, and three pairs of mutually abutting stops, one stop of each pair being fixed on one of said floor legs, the other stop of two of said pairs being fixed on said rigid board, and the other stop of the third of said pairs being fixed on said rigid hip leg, said stops in each of said pairs mutually engaging in a manner to permit and restrict swinging movement of all of said floor legs from overlapping relation to said rear surface of said board to positions extending away from said work board, whereby said legs are precluded from swinging into overlapping relation to said front face of the board, together with a channel-shaped shelf

rest having a rest surface whose overall width is flanked by channel forming flanges pivotally mounted at one end on each of two of said floor legs so that said rest surface and flanges swing between a position saddling the leg and a position projecting forward from the leg on which the shelf rest is mounted.
